United States Patent

Des. 242,139

Patented Nov. 2, 1976

242,139

DATA DISPLAY INDICATOR FOR AN ATHLETIC EVENT OR THE LIKE

Lloyd S. Turner, Los Gatos, Calif., assignor to Hind-Wells, Inc., San Luis Obispo, Calif.

Filed Jan. 9, 1975, Ser. No. 539,719

Term of patent 14 years

Int. Cl. D19—04

U.S. Cl. D19—26

FIG.
1.

FIG. 2.

FIG.
3.

FIG. 1 is a perspective view of a data display indicator for an athletic event or the like showing my new design;

FIG. 2 is a top plan view; and

FIG. 3 is a rear perspective view.

I claim:

The ornamental design for a data display indicator for an athletic event or the like, as shown.
